UNITED STATES PATENT OFFICE.

WILLIAM W. HARRISON AND JOHN HOLT, OF PAWTUCKET, RHODE ISLAND,
ASSIGNORS OF ONE-THIRD TO CHARLES E. PERVEAR, OF PAWTUCKET,
RHODE ISLAND.

WEFT-MOTION FOR HAIRCLOTH-LOOMS.

SPECIFICATION forming part of Letters Patent No. 691,375, dated January 21, 1902.

Application filed January 17, 1900. Renewed June 13, 1901. Serial No. 64,476. (No model.)

To all whom it may concern:

Be it known that we, WILLIAM W. HARRISON and JOHN HOLT, of Pawtucket, in the county of Providence and State of Rhode Island, have invented certain new and useful Improvements in Weft-Motions for Haircloth-Looms; and we do hereby declare that the following is a full, clear, and exact description thereof, reference being had to the accompanying drawings, and to the letters of reference marked thereon, which form a part of this specification.

This invention relates to looms for weaving haircloth, and more especially to the mechanism for operating the nippers that select the hairs to form the weft or filling of the cloth. It is fully explained and illustrated in this specification and the accompanying drawings.

Figure 1 shows a front elevation of a portion of a loom-lay with parts of the loom immediately connected with the nipper-motion. Fig. 2 represents an end elevation of a loom with the nipper-motion. Fig. 3 is a perspective view of the nipper-motion with some parts of the loom.

The object of this invention is to make the operation of the nipper-motion more certain and to be depended upon by making all its parts of metal or wood and not depending on straps of leather or like yielding material.

The construction and operation are as follows:

A is the end frame of the loom.

D is the main shaft, with a driving-pulley P' on it, and J is one of the cranks on the shaft D that operate the lay B.

C is a double or positive cam—that is, it gives a positive motion both ways.

N is a vertical plate made flat and broad in its upper half and having a slot made in it that slides on the main shaft D between the hub of the crank J and the cam C and is guided at its lower end, which is made round, in a stand I, fast on the end frame A. The cam has a heart-shaped groove S in its outer side, in which a friction-roll R, held on a stud in the plate N, travels and gives an up-and-down motion to the plate.

E is a connecting-bar the upper end of

which is held between ears on the plate N by a pin G, on which the bar has a limited swinging motion, and its lower end is held on a pin in the outer end of the arm P, fast on a horizontal rocker-shaft H, which is held in bearings in the stands L L, fast to the floor. In this way a rocking motion is given to the shaft H by the cam C every time the shaft D and cam revolve and the lay beats up.

On the front of one end of the lay B a dovetailed bar K is attached to form ways for the clamp V to slide on. The clamp V has a stud Z in its face, which stud is fitted to slide in a slot in the upper end of what may be called a "picker-stick" F, as it performs the function of placing the filling in the warp. The picker-stick F swings back and forth with the lay on a pin T, held in a shoe W, which is held on a pin in a step O, fast on the floor, to swing in and out from the end frame A. (See dotted lines in Fig. 1.) This latter motion is given to the stick F by the connecting-rod X, one end of which is pivoted to the shoe W and the other end to the arm Y, fast on one end of the rocker-shaft H. (See Fig. 1.)

The nipper-bar A', with the nipper M, is held at its outer end on a block C', which slides in ways made on the top of the lay B. This block C' has a pin D' in it (see Fig. 2) that connects it to an ear on the top of the clamp. It will readily be seen that the motion required to push the nipper-bar through the shed of the warp and return it again is obtained from the cam C through the sliding plate N operating the rocker-shaft H by the connecting-rod to arm P and the rocker-shaft H operating the picker-stick F by means of the arm Y and the connecting-rod X, and as all these parts are rigid the motion of the nipper as to distance and time will always be the same with regard to the movements of the other parts of the loom. By setting the arm C on the shaft D properly with regard to the position of the crank J that moves the lay and shaping the cam to allow the required amount of dwell for the friction-roll to allow the lay to beat up a certainty and accuracy of the motion of the nipper-bar can be counted on that will admit of a considerable in-

crease in the speed of the loom and at the same time improve the product.

Having thus described our improvements, we claim as our invention and desire to secure 5 by Letters Patent—

In a haircloth-loom the combination of a picker-stick a nipper-bar connected thereon, a shoe pivoted in a step fast on the floor to hold the picker-stick, a pin passing through 10 sides of said shoe and the picker-stick to allow the stick to move with the lay, a main shaft, a double cam fast thereon, a vertically-slid-

ing plate with a friction-roll operated by said cam, and means for operating said picker-stick by said plate and friction-roll, substantially as described. 15

In testimony whereof we have hereunto set our hands this 6th day of January, A. D. 1900.

WILLIAM W. HARRISON.
JOHN HOLT.

In presence of—

H. E. BARLOW,
BENJ. ARNOLD.
